UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

1,342,573.

Specification of Letters Patent.

Patented June 8, 1920.

Application filed December 24, 1918. Serial No. 268,140.

To all whom it may concern:

Be it known that I, ALONZO E. RHOADES, a citizen of the United States, residing at Hopedale, county of Worcester, State of Massachusetts, have invented an Improvement in Automatic Filling-Replenishing Looms, of which the following description, in connection with the accompanying drawing, is a specification, like characters on the drawing representing like parts.

This invention relates to automatic filling replenishing looms in which when the filling needs to be replenished a fresh filling carrier is transferred from a hopper or supply mounted above the lay to the lay and the spent filling carrier is ejected through a slot in the lay. The invention is particularly applicable to looms of the well known Northrop type in which the filling carrier is a bobbin and in which when replenishment takes place the bobbin is transferred from the hopper to the shuttle on the lay; the fresh bobbin ejecting the spent bobbin from the shuttle and through the slot in the lay. In this general type of loom the slot in the lay through which the ejected filling carrier passes is the slot in which the picker stick oscillates. To guide the ejected filling carrier into a suitable receptacle the cutaway or slotted part of the lay is usually provided with an inclined chute having a part thereof of upwardly extending beyond the inner end of the path of the picker stick and some means is provided to prevent the ejected filling carrier from entering the slot between the extended portion of the chute and the picker stick because if this happens the picker stick would jam on its next inward stroke causing more or less damage. In the patent to Janelle No. 951,949 granted March 15, 1910, a guard pivotally mounted on the lay is provided. This guard normally covers the slot and is swung out of position at each inward movement of the picker stick by the picker stick coming into contact therewith and camming it into open position.

The present invention provides a movable guard for the slot between the extended portion of the chute and the picker stick which is normally maintained in open position so that the picker stick may reciprocate freely in the slot without contacting with the guard and the invention also provides for causing the guard to be moved into closed position to

guide the ejected filling carrier whenever filling replenishment is called for by the operation of the loom or whenever the filling carrier is ejected.

Preferably the invention also has for its object to provide for the operation of the movable guard into closed or guiding position by or through the action of the transferring mechanism of the loom.

The invention also has for its object to provide means in connection with the movable guard for catching and retaining the trailing end from the ejected filling carrier and this means preferably consists of a serrated upper edge upon the movable guard. If this trailing filling end be not caught and held it is likely to be carried back by the shuttle and thrown or woven into the shed causing an imperfection while if it be caught and retained it will reave out through the eye of the shuttle as the shuttle is picked across the loom.

These and other objects of the invention will appear more fully from the accompanying description and drawings and will be particularly pointed out in the appended claims.

The drawings show so much of an automatic filling replenishing loom of the Northrop type as is necessary to a disclosure of the invention together with a preferred form of the invention embodied therein.

In the drawings—

Figure 1 is a front elevation of a portion of the replenishing end of the loom, a preferred embodiment of the present invention being illustrated in connection therewith;

Fig. 2 is a view on a somewhat larger scale taken on transverse vertical section showing the position of the dogs on the transferer when the bunter for operating the movable guard comes into contact with the dog on the transferer upon the beat up following a call for filling replenishment;

Fig. 3 is a detail similar to Fig. 2 showing the position of the co-operative portion of the dogs and bunters at the conclusion of the beat-up;

Fig. 4 is an end elevation partially in transverse vertical section of the loom shown in Fig. 1 with the parts in the normal position they occupy when the loom is running.

Fig. 5 is a view similar to Fig. 4 with some of the parts omitted and some removed and showing the dogs on the transferer in

operative position such as they occupy upon the call for filling replenishment;

Fig. 6 is a front elevation of the end of the lay on a somewhat larger scale than in Fig. 5 1 showing the parts in their normal position;

Fig. 7 is a view in transverse vertical section taken on the line 7—7 of Fig. 6;

Fig. 8 is a view similar to Fig. 7 showing the guard in closed position;

10 Fig. 9 is a detail in transverse vertical section of the spring pressed plunger and coöoperating parts by means of which the guard is yieldingly held in open position, the parts being shown in the position which 15 they occupy when the guard is in closed position;

Fig. 10 is a view similar to Fig. 9 the parts being shown in the position which they occupy when the guard is in open position.

20 The general construction of a loom of this type is so well known and familiar to those skilled in the art that only a very general description of those parts directly concerned 25 with the present invention is necessary.

A rotary hopper 11 containing the supply of fresh filling carriers 12 is mounted by the hopper stand 13 upon the top of the breast beam 14 so as to extend above the 30 lay. The fresh filling carriers are discharged successively as required from the hopper by a transferer 15 pivoted upon the hopper stand at 16 and provided with a depending arm 17 having pivotally mounted thereon 35 at its lower end a dog carrier 18 in which is adjustably mounted by means of the set screw 19 a transfer dog 20.

The lay 21 beats back and forth beneath the hopper and carries on its upper face the 40 shuttle box 22 which receives the shuttle 23 at the end of the pick. The shuttle box and the lay therebeneath are vertically slotted at 25 first to permit the movement of the picker stick 26 and second to provide for the 45 passage of the spent filling carrier when ejected from the lay or in the case of a bobbin from the shuttle on the lay.

A transferer bunter 27 is secured to and projects rearwardly from the face of the 50 lay opposite the dog 20.

In this type of loom when the filling on the running filling carrier has reached a pre-determined degree of exhaustion or has been exhausted suitable indicating mechanism is set in motion calling for replenishment and in the type illustrated this mechanism acts to swing the dog carrier 18 about its pivot and raise the transferer dog 20 into the path of the bunter 27 so that as the 60 lay beats up the bunter 27 contacting with the dog 20 will effect the actuation of the transferer and cause a fresh filling carrier to be discharged from the hopper into the shuttle on the lay then therebeneath and to

eject the exhausted or spent filling carrier 65 from the shuttle down through the slot or opening in the lay.

In order to guide the ejected filling carrier into a suitable receptacle such as is usually placed on the transferer end of the 70 loom the slotted end of the lay is provided with an inclined chute shown as a metal plate 28 carried by a bracket 29 bolted in place at 30 to the lay. This chute extends upwardly beyond the inner end of the path 75 of the picker stick and at its upper edge contacts with the rearward wall of the slot or opening 25 in the lay. It is obvious that the outer edge 31 of this inclined chute must be so located as not to interfere with 80 the picker stick at 26 at the end of the reciprocation of the picker stick. Consequently, when the picker stick is at the outer end of its reciprocation the slot or opening 85 in the chute between the picker stick and the edge 31 is left open and unprotected and the filling carrier when ejected is likely to fall into this slot and to be caught between the picker stick and the chute upon the next pick which results in injury of the 90 loom and breakage of the parts.

In order to protect this open portion of the chute a movable guard is provided. This guard is shown as a plate 32 pivoted or journaled at its lower edge on a shaft 33 mounted 95 in the chute 28 and its bracket 29. This plate is adapted when swung into its rearward or closed position to lie substantially in the same plane as the upper portion of the chute 28 and with its upper edge resting 100 against the rear wall of the slot 25. This plate when swung into its forward or open position stands substantially vertically and out of the way of the reciprocation of the picker stick so as to leave the slot 25 free 105 for the movement of the picker stick.

The guard is normally held in its open position and is moved into its closed position only when transfer is to take place or a filling carrier is to be ejected through the 110 slot 25. A simple and preferred mechanism for controlling the movement of the guard to subserve these ends is illustrated.

An actuator shaft 34 is journaled on the front face of the lay above the guard and 115 for that purpose is shown as journaled in brackets 35 projecting from the shuttle-box. This shaft 34 at its outer end is provided with a depending arm 36 connected by a link 37 to the upper end of a bracket 38 120 rigidly secured to the guard 32. A split head 39 is clamped on the shaft 34 and arm 36 by the bolt 40 and this head is provided with a flat face 41. A bracket 42 is bolted to the face of the lay by bolts 43 and carries 125 at its inner end a socket 44 in which is mounted a plunger 45 having a head 46. A helical spring 47 surrounds the plunger

in the socket 44 bearing against the bottom of the socket and the bottom of the head and thus acts normally to project the plunger upwardly. The upper surface 48 of the plunger head is flat and is so positioned as to come opposite the flat surface 41 on the split head 39. These parts are so arranged that when they are in the position illustrated in Fig. 10 the spring pressed 10 plunger will hold the shaft 34 in such an angular position that the guard 32 will be held in its open position as shown in Fig. 7. Consequently any movement of the guard away from this position will be resisted by the spring pressed plunger which thus acts at all times normally to restore the guard to its open position. The depending arm 36 is also arranged when the guard is in open position to contact with a stop 15 49 projecting laterally from the socket portion 44 of the bracket 42.

The actuator shaft 34 at its inner end is provided with a depending arm 50 to form a guard bunter so arranged that if this 20 bunter be struck the shaft 34 will be rocked to swing the guard rearwardly to its closed position. Any suitable means may be used for thus moving the actuator shaft 34 when the guard is required to be in closed position 25 but as a preferred means a dog is provided on the transferrer.

The dog carrier 18 is shown as prolonged downwardly at 51 and in this prolongation is mounted a guard dog 52 of 30 generally similar construction to the usual transferrer dog 20. This dog is longitudinally adjustable in the carrier by means of the set screw 53 in the usual manner. The face 54 of the dog 52 is preferably 35 caved. The parts are so adjusted and arranged that upon the call for filling replenishment when the dog carrier 18 is swung to raise the transferrer dog 20 into the path of the bunter 27 the guard dog 52 will be 40 raised into the path of the guard bunter 50. But the guard dog 52 is adjusted so as to to be engaged by the bunter 50 before the bunter 27 engages the transferrer dog 20 and consequently as the lay beats up after 45 the call for filling replenishment the guard 32 will be swung into closed position before the bunter 27 engages the dog 20 and effects the transfer of a fresh filling carrier and the consequent ejection of the spent filling 50 carrier. This movement of the bunter 50 to rock the shaft 34 and swing the guard into closed position is indicated in its final stage in Fig. 3 where the movement has been completed and the bunter 27 has just engaged the dog 20.

It will thus be seen that as transfer takes place the slot through the chute is closed and the ejected filling carrier must pass down over the face of the guard 32 and 55 the chute 28 and there is no danger of the

ejected filling carrier being caught where it will be jammed by the picker stick upon the next pick.

As the lay beats back after replenishment has taken place the bunter 50 swings away 70 from the dog 52 and the spring pressed plunger 45 at once acts to restore the guard to open position immediately allowing free passage for the reciprocation of the picker stick.

If as is usual in connection with automatic filling replenishing looms where replenishment takes place prior to complete exhaustion of the running filling and the filling still remains upon the filling carrier 80 after its ejection the trailing end will extend from the ejected filling carrier up through the slot 25 in the lay to the shuttle and out through the eye of the shuttle toward the fell of the cloth to a point where it 85 has been severed. If this trailing end is not removed from the shuttle it is likely on the next pick of the shuttle to be caught and carried or thrown back into the shed and woven into the cloth causing an imperfection. In the present invention this is prevented by providing means on the guard 32 catching and retaining the trailing filling end and this means is preferably constituted as a serrated edge 55 formed at the upper 90 edge of the guard. Immediately after the spent filling carrier has been ejected the lay swings rearwardly and consequently the guard swings to open position bringing the serrated edge directly across the path of the 100 trailing filling end so that as the shuttle is picked across the loom this trailing filling end is caught by the serrations and held and drawn out through the eye of the shuttle.

Having fully described my invention what 105 I claim as new and desire to secure by Letters Patent is:

1. An automatic filling replenishing loom comprising means for ejecting a spent filling carrier from the lay, a lay longitudinally slotted for the passage of the ejected filling carrier, a guide chute carried by the lay beneath the lay slot and provided with a slot at its outer end, a picker stick reciprocating in the said slots, and means carried 110 by the lay and governed by the means for ejecting the spent filling carrier, acting to prevent the passage of the ejected filling carrier through the slot in the chute when the picker stick is at the outer end of its 115 stroke.

2. An automatic filling replenishing loom comprising means for ejecting a spent filling carrier from the lay, a lay longitudinally slotted for the passage of the ejected 120 filling carrier, a picker stick reciprocating in the slot, a guide chute extending beyond the inner end of the picker stick path, and means carried by the lay and governed by the means for ejecting the spent filling car- 130

- rier acting to prevent the passage of the ejected filling carrier through the slot between the extended portion of the chute and the picker stick.
5. 3. An automatic filling replenishing loom comprising means for ejecting a spent filling carrier from the lay, a lay longitudinally slotted for the passage of the ejected filling carrier, a guide chute carried by the 10 lay beneath the lay slot and provided with a slot at its outer end, a picker stick reciprocating in the said slots, a movable guard acting when in closed position to close the slot in the chute to prevent the passage of the 15 ejected filling carrier therethrough when the picker stick is at the outer end of its stroke, and means acting upon the beat-up of the lay at which replenishment is to take place to move the guard into closed position.
20. 4. An automatic filling replenishing loom comprising means for ejecting a spent filling carrier from the lay, a lay longitudinally slotted for the passage of the ejected filling carrier, a guide chute carried by the 25 lay beneath the lay slot and provided with a slot at its outer end, a picker stick reciprocating in the said slots, a movable guard acting when in closed position to close the slot in the chute to prevent the passage of the 30 ejected filling carrier therethrough when the picker stick is at the outer end of its stroke, means acting normally to maintain the guard in open position to permit the reciprocation of the picker stick, and means acting 35 upon the beat-up of the lay at which replenishment is to take place to move the guard into closed position.
5. An automatic filling replenishing loom comprising means for ejecting a spent filling carrier from the lay, a lay longitudinally slotted for the passage of the ejected filling carrier, a guide chute carried by the 40 lay beneath the lay slot and provided with a slot at its outer end, a picker stick reciprocating in the slot, a movable guard acting when in closed position to close the slot in the chute to prevent the passage of the ejected filling carrier therethrough when the picker stick is at the outer end of its stroke, 45 and means acting upon the beat-up following a call for filling replenishment to move the guard into closed position.
6. An automatic filling replenishing loom comprising means for ejecting a spent filling 50 carrier from the lay, a lay longitudinally slotted for the passage of the ejected filling carrier, a picker stick reciprocating in the slot, a guide chute extending beyond the inner end of the picker stick path, a movable 55 guard carried by the lay to close the slot between the extended portion of the chute and the picker stick when at the outer end of its stroke, means acting normally to maintain the guard in open position to permit 60 the reciprocation of the picker stick, means 65

governed by the means for ejecting the spent filling carrier to move the guard into closed position.

7. An automatic filling replenishing loom comprising a lay longitudinally slotted for the passage of the ejected filling carrier, a hopper containing fresh filling carriers mounted above the lay, a movable transfer to transfer a fresh filling carrier from the hopper to the lay and eject the spent filling carrier therethrough, a guard pivotally mounted on the lay acting when swung into open position to permit the reciprocation of the picker stick and when swung into closed position to cross the path of the picker stick and guide the passage of the ejected filling carrier when the picker stick is at the outer end of its stroke, means acting normally to maintain the guard in open position to permit the reciprocation of the picker stick, a guard bunter operatively connected to said movable guard, a dog movably mounted on the transfer and movable upon the call for filling replenishment into the path of the guard bunter, the said guard bunter when the lay beats up after the call for filling replenishment striking the dog and effecting the swinging of the guard to closed position to receive and guide the ejected filling carrier. 95

8. An automatic filling replenishing loom comprising means for ejecting a spent filling carrier from the lay, a lay longitudinally slotted for the passage of the ejected filling carrier, a picker stick reciprocating in the slot, a guard movably mounted on the lay to cross the path of the picker stick and guide the passage of the ejected filling carrier, an actuator movably mounted on the lay, connections between said actuator and guard whereby the movement of the guard is effected by the movement of the actuator, a bunter projecting from the actuator, and means controlled by or through the call for filling replenishment to strike the bunter as the lay beats up and thereby to effect the movement of the actuator to swing the guard to closed position. 100

9. An automatic filling replenishing loom having the construction defined in claim 8 together with means acting as the lay beats back after the ejection of the filling carrier to swing the guard to and maintain the guard in open position. 115

10. An automatic filling replenishing loom comprising means for ejecting a spent filling carrier from the lay, a lay longitudinally slotted for the passage of the ejected filling carrier, a picker stick reciprocating in the slot, a guard movably mounted on the lay to cross the path of the picker stick and guide the passage of the ejected filling carrier, an actuator shaft journaled on the face of the lay above the guard, connections between said shaft and guard for operating 120

125

130

the former from the latter, means for normally holding the guard in open position, a bunter on said shaft, a dog movable into the path of the bunter upon the call for filling 5 replenishment, whereby when the lay beats up after the call for filling replenishment the bunter will strike the dog and rock the shaft and swing the guard to closed position.

11. An automatic filling replenishing 10 loom having the construction defined in claim 8 together with a spring-pressed plunger mounted on the lay and cooperating with the actuator to maintain it yieldingly in a position that will maintain the guard 15 in open position.

12. An automatic filling replenishing 20 loom having the construction defined in claim 3 together with means on said guard for catching and retaining the trailing filling 25 end from the ejected filling carrier.

13. An automatic filling replenishing loom having the construction defined in 25 claim 3 in which the said movable guard is serrated at its upper edge to catch and retain the trailing filling end from the ejected filling carrier.

14. An automatic filling replenishing loom having the construction defined in claim 8 together with means acting as the

lay beats back after the ejection of the 30 filling carrier to swing the guard to and maintain the guard in open position, and means on the guard for catching and retaining the trailing filling end whereby as the lay beats back after the ejection of the 35 filling carrier and the guard swings to open position the said means on the said guard will catch the trailing end from the ejected filling carrier and cause the end to be cleared from the shuttle as it is picked across the 40 lay.

15. An automatic filling replenishing loom having the construction defined in 45 claim 8 together with means acting as the lay beats back after the ejection of the filling carrier to swing the guard to and maintain the guard in open position, and serrations along the upper edge of the said guard whereby as the lay beats back and the guard swings to open position the trailing 50 end from the ejected filling carrier will be caught by the serrated edge of the guard and cleared from the shuttle as it is picked across the lay.

In testimony whereof I have signed my 55 name to this specification.

ALONZO E. RHOADES.
